UNITED STATES PATENT OFFICE.

COSBY CRITTENDEN COOKE, OF LOGAN, WEST VIRGINIA.

DENTAL THREAD HOLDER.

Application filed December 16, 1922. Serial No. 607,344.

To all whom it may concern:

Be it known that I, COSBY C. COOKE, a citizen of the United States, and resident of Logan, in the county of Logan and State of West Virginia, have invented certain new and useful Improvements in Dental Thread Holders, of which the following is a specification.

This invention relates to cord holders especially adapted for use in cleaning one's teeth.

Briefly stated an important object of this invention is to provide novel means whereby a piece of dental floss or silk may be held in an operative position and moved longitudinally between one's teeth without the necessity of the operator's hand coming directly in contact with the floss.

Further the invention forming the subject matter of this application aims to provide a dental cord or thread holder which is of highly simplified construction, compact and cheap to manufacture.

Other objects and advantages will be apparent during the course of the following description.

In the accompanying drawing, forming a part of this application, and in which like numerals are employed to designate like parts throughout the same.

Figure 1 is a perspective of the improved dental thread holder,

Figure 2 is a plan view of the improved thread holder and reciprocator, a part of the thread container being broken away,

Figure 3 is a side elevation of the improved thread holder, parts being shown in section,

Figure 4 is a vertical transverse sectional view taken on line 4—4 of Figure 2.

Figure 5 is a detail sectional view taken on line 5—5 of Figure 2,

Figure 6 is an end elevation illustrating the cord holding member,

Figure 7 is a perspective illustrating the cord holding block which is mounted on the cord reciprocating member.

Figure 8 is a perspective of the main cord holding member.

In the drawing wherein for the purpose of illustration is shown a preferred embodiment of the invention, the numeral 10 designates what might be said to be a shank while the numeral 11 designates a thread container of bulb-shaped formation.

In carrying out the invention the shank 10 has connection at its forward end with a holder 12 having spaced parallel arms 14 adapted for holding a piece of thread 15 in an operative position. More specifically 60 the parallel arms 14 are provided with transverse slots 16 which extend out through opposite sides of the arms for the reception of the cord and the outer sides of the arms 14 are provided with longitudinal grooves 17 65 for the reception of the thread or floss.

The holder 12 which is of U-shaped formation is adapted to support the cord 15 so that the same may be drawn between the teeth for removing food or foreign matter 70 which has lodged between the teeth.

In the operation of the improved dental thread holder the U-shaped member 12 is rotated about a pivot pin 18 by means of which the holder is pivotally connected to 75 the forward portion of the shank 10.

Figures 1 and 2 illustrate that the thread holder 12 may be turned about the axis of a pivot bolt 18 by a stem 20 having its forward end provided with a small gear 21 80 which meshes with the arcuate rack 22 formed on the bight portion 24 of the U-shaped member 12. It will be seen that when the stem 20 is turned the gear 21 will be rotated for moving the U-shaped holder 12 about the axis of the pivot pin 18 whereupon the threads will be urged into engagement with the edges of one's teeth for thoroughly removing those foreign particles which have lodged between the teeth. 90

The stem 20 which is connected to the shank 10 by means of bearings 30 may be rocked by means of oppositely projecting arms 32 secured by means of the attaching portion 33 to the intermediate portion of the 95 stem and the arms 32 are curved longitudinally so as to provide a convenient means whereby the same may be engaged by the fingers or the thumb of the operator. Figure 5 illustrates that the stem 10 is formed 100 with a recess 136 to partially receive one of the arms 32 whereby the stem 20 may be rocked to an extent sufficient to impart the desired movement to the U-shaped member 12. 105

Figure 2 clearly illustrates that the bulb-shaped container 11 receives a quantity of dental floss or thread 36 which is passed through a slot 37 in the container and along the shank 10. 110

As illustrated in Figure 1 the cord is now trained about a guiding stem 40 formed at one side of the head 41 formed on the forward end of the stem 20. The cord after being trained about the pin 40 passes downwardly through one of the grooves 17 and through the slot 16, after which the cord passes up through the other groove 17 and is engaged in a cord holding notch 46 in one side of the head 41. The free end portion of the cord or thread as the case may be is detachably connected to a cleat 47 secured on the upper side of the head.

It will be observed that the cleat 47 is arranged at one side of the longitudinal center of the head 41 while the pin 40 is located at the other side so that when the stem is rocked the cord or thread is reciprocated. That is to say when the head 41 is rocked about the longitudinal axis of the stem 20 as the result of the rotation of the stem, the thread will also be moved and that part of the thread between the forward end portions of the arms 14 will be moved backward and forward for removing foreign matter from between the teeth.

It will be observed that the gear 21 is formed on the underside of the head 41 and when the head 41 is rocked the U-shaped holder 12 is moved about the axis of the pivot pin 18 simultaneously with the longitudinal movement of the tooth contact portion of the thread whereby the teeth are thoroughly and expeditiously cleaned at their opposed edges.

When it is desired to place a new portion of thread in an operative position, additional thread may be drawn from the container by depressing the spring actuated plunger 50, which as illustrated in Figure 4 has connection with one of a pair of jaws 51 between which the thread is located. The spring actuated jaws 51 grip the thread and thereby prevent more thread than is necessary from being withdrawn from the container.

However when desired the plunger 50 may be depressed for allowing additional thread to be withdrawn. Of course when additional thread has been withdrawn the old thread may be severed at the proper point by means of a cutter 55 secured on the head 41 rearwardly of the cleat 47.

When the laterally projecting arms 32 are moved in one direction by the operator they are returned to their original position by means of a spring member 60 anchored to one section of the bulb-shaped container as indicated at 61 and connected to the laterally projecting member 63 of the stem as indicated at 64.

In operation the thread 15 is set for use in the manner illustrated in Figure 1 and the stem 20 is subsequently rocked for im-

whereupon the tooth contact portion of the thread is moved backward and forward for cleaning the teeth. Simultaneously with the movement of the thread the U-shaped member 12 is moved about the axis of the pin 18 for moving the thread into engagement with all edges of the teeth.

With reference to the foregoing description taken in connection with the accompanying drawing it will be apparent that the device is capable of cleaning the teeth without bringing the hands of the operator directly into contact with the thread and furthermore it is not necessary to put one's hands into the mouth. Thus an extremely sanitary and efficient cleaner is provided which is simple to keep clean and cheap to manufacture, all of which contributes to the desirability of the article.

The stem 20 may be retracted slightly when it is desired to break the connection between the rack 22 and the gear 21 so that the position of the member 12 may be changed. This permits the teeth in all parts of the mouth to be cleaned.

Furthermore as illustrated in Figure 7, the block 98 which supports the cleat 47, is urged rearwardly by a spring 99 so that the thread is at all times held taut.

Having thus described the invention, what is claimed is:

1. A dental thread holder comprising a U-shaped member having a pair of thread holding arms, and a shank pivotally supporting the holder for movement about an axis at right angles to the longitudinal axis of the shank.

2. A dental thread holder comprising a shank, a U-shaped thread holding member pivoted to the forward portion of the shank and having thread holding arms, a thread slidably connected to said arms, and means whereby to reciprocate said thread and simultaneously rock said U-shaped member.

3. A dental thread holder comprising a shank, a thread holder pivoted to the forward portion of the shank and having arms, a thread connected to said arms, a stem rotatably connected to the shank and having a head, the opposite edges of which have connection with said thread, and means whereby to rotate said stem for reciprocating that portion of the thread between said cord holding arms.

4. A dental thread holder comprising a shank, a thread holder pivoted to the forward portion of the shank and having arms, a thread connected to said arms, a stem rotatably connected to the shank and having a head, the opposite edges of which have connection with said thread, means whereby to rotate said stem for reciprocating that portion of the thread between said cord holding arms, there being a gear and rack connection between the head and the cord

holding member for moving the cord holding member about an axis at right angles to the longitudinal axis of the shank.

5. A dental thread holder comprising a shank, a thread container connected to the rear portion of the shank, a holder pivoted to the forward portion of the shank, and having a pair of parallel arms, a stem extending longitudinally of and rotatably connected to said shank, a head secured to the forward portion of the stem and projecting laterally of the stem, the opposite sides of said head being provided with thread engaging means arranged rearwardly of said arms, said arms also being provided with thread engaging means, operating members connected to said stem and adapted to be engaged by the hand of the operator in rocking the stem, a rack connected to said thread holding member, a gear secured to said head and engaging said rack for rocking the thread holding member, and a cord cutter associated with the head.

6. A dental thread holder comprising a shank, a thread holder pivoted to the forward portion of said shank, a stem mounted on the shank and having a head, there being a gear and rack connection between said pivoted thread holder and said head whereby the rocking of said stem will turn said thread holder, and means whereby said stem may be manually rocked.

7. A dental thread holder comprising a thread holding member, means pivotally supporting the thread holding member, a head having a gear and rack connection with the thread holding member and having means whereby a thread may be connected thereto, said thread holding member being provided with spaced arms between which the thread is extended, and means whereby to rock said head for reciprocating the thread and turning said thread holding member.

COSBY CRITTENDEN COOKE.
